CLAIM

The ornamental design for an orthodontic pacifier as shown and described.

DESCRIPTION

FIG. 1 is a top, rear perspective view of an orthodontic pacifier, showing our new design;

FIG. 2 is a bottom, front perspective view of the orthodontic pacifier of FIG. 1;

FIG. 3 is a top, front perspective view of the orthodontic pacifier of FIG. 1;

FIG. 4 is a front view of the orthodontic pacifier of FIG. 1;

FIG. 5 is a rear view of the orthodontic pacifier of FIG. 1;

FIG. 6 is a left side view of the orthodontic pacifier of FIG. 1;

FIG. 7 is a right side view of the orthodontic pacifier of FIG. 1;

FIG. 8 is a top view of the orthodontic pacifier of FIG. 1; and,

FIG. 9 is a bottom view of the orthodontic pacifier of FIG. 1.

The broken lines depict portions of the orthodontic pacifier that form no part of the claimed design.

1 Claim, 6 Drawing Sheets
